(57) **CLAIM**

I claim the ornamental design for a nipper blade, as shown and described.

DESCRIPTION

FIG. 1 is a front upper perspective view of the nipper blade showing my new design;

FIG. 2 is a rear elevation view thereof;

FIG. 3 is a front elevation view thereof;

FIG. 4 is a left side elevation view thereof, with the right side elevation view being a mirror image thereof;

FIG. 5 is a top plan view thereof with the bottom plan view being a mirror image thereof;

FIG. 6 is a front upper perspective view of an alternative embodiment of the nipper blade FIG. 1;

FIG. 7 is a rear elevation view thereof;

FIG. 8 is a front elevation view thereof;

FIG. 9 is a left side elevation view thereof, with the right side elevation view being a mirror image thereof; and,

FIG. 10 is a top plan view thereof, with the bottom plan view being a mirror image thereof.

The broken lines shown represent unclaimed subject matter and form no part of the claimed design.
